ATTORNEY

UNITED STATES PATENT OFFICE

2,266,291

HEAT EXCHANGER

Fred M. Young, Racine, Wis.

Application January 16, 1939, Serial No. 251,076

1 Claim. (Cl. 257—144)

The present application is a continuation in part of my application Serial No. 735,999, filed July 19, 1934.

An object of the present invention is to provide a heat exchanger adapted to occupy the horizontal space in a vertically positioned housing and having two separate cores operatively connected together at one end by a single header, the other ends each having individual headers, one being positioned above the horizontal plane of the single header and the other below the horizontal plane of the single header, the upper header of the pair of headers having an inlet connection and the lower header of the pair of headers having an outlet connection whereby liquid may flow from the inlet header to the outlet header by gravity.

A further object of the present invention is to provide a connection between the inner ends of the pair of headers adapted to permit independent expansion and contraction of the separate banks of tubes but prevent the headers from moving longitudinally or vertically relative to each other.

To these and other useful ends, my invention resides in features of construction, and combination of parts or their equivalents, as hereinafter set forth and claimed and shown in the accompanying drawing in which:

Fig. 1 is a top view of my improved heat exchanger.

Fig. 2 is a side view of the device shown in Figure 1.

Fig. 3 is an end elevational view of the device shown in Figures 1 and 2.

Fig. 4 is an enlarged fractional side view of the side plates which are adapted to cooperate with the headers to form a frame.

My improved heat exchanger when completed, forms a strong, compact, unitary structure which may be easily installed at the factory, crated and shipped individually to the place of installation and easily installed in the cabinet or air duct.

My device comprises two separate banks of tubes 12 and 12^a having a multiplicity of closely spaced strip fins 13 and 13^a through which the tubes extend forming separate cores.

I provide a single header 14, long enough to receive the ends of tubes 12 and 12^a. This header is preferably provided with a flange 15, with which to attach the end of the unit to the wall of the cabinet.

Each core at the other end is provided with individual headers 16 and 17. The tubes of each

core diverge from header 14 as clearly indicated in Figures 4 and 5. Headers 16 and 17 are on a horizontal line positioned a distance apart vertically, preferably equal to about the width of a header as indicated in Figures 2 and 3.

Headers 16 and 17 are provided with inlet and outlet openings 20 and 21, which are positioned preferably at the outer ends of the headers. Thus a heating or cooling liquid or gas may enter at 20, pass through one core, then through header 14 and return through the other core to outlet 21. The path is thus equalized for the passage of the heating or cooling medium and the cores may expand and contract individually. Thus it will be seen that the heating or cooling medium or condensate may drain downwardly through all of the tubes.

One of the novel features of my device is that headers 16 and 17 are tied together by means of spaced apart ears 22 and 23 and bolt 24. Thus while the separate banks of tubes may expand in a direction parallel to the tubes, they will be anchored against individual transverse or vertical movement by headers 16 and 17. The unit therefore will be practically as strong as if headers 16 and 17 were made integral.

In order to provide protection for the fin edges I provide side plates 25, which are attached to the headers as at 26, by means of drive screws 27. The screw openings in these plates are elongated as at 28. Thus after the cores are completed the plates may be easily attached because provision is made for slight variations in the distance between headers, and further, after the unit is put in service the oblong holes 28, will provide for slight unequal expansion between the tubes and plates.

Header 14 may be rigidly secured to one wall of the duct or cabinet. Headers 16 and 17 are preferably secured to the opposite wall of the cabinet so they are free to move longitudinally of the tubes.

One of the advantages of my device is that it may be handled without danger of injuring the tubes before being installed in the cabinet because the pair of headers is secured together. Otherwise if one should lift one end of the device by one of the pair of headers only, the weight of the other header and its tubes might injure the tubes. In this connection, it will be noted that the cores may consist of but a single row of tubes and therefore they are not very rigid.

Clearly many minor detail changes may be made without departing from the spirit and scope

of the present invention as recited in the appended claim.

Having thus shown and described my invention, I claim:

A device of the class described, comprising an elongated horizontally positioned header, a pair of headers spaced a distance from and arranged in parallel relation with each other and with said first header, their inner ends being in juxtaposition, said pair of headers having a combined length about equal to said first header, one of said pair of headers being positioned somewhat above and the other somewhat below the horizontal plane of said first header, rows of substantially straight tubes forming operating connections between said first and said pair of headers, closely spaced fins through which said tubes

5 extend forming two separate cores whereby the tubes of one core incline downwardly from one of said headers of said pair of headers to said first header and the tubes of the other core incline downwardly from said first header to the other of said pair of headers, an inlet connection in the upper header of said pair of headers and an outlet connection in the lower header of said pair of headers whereby a liquid may flow by gravity from said inlet to said outlet, said pair of headers having a connection therebetween adapted to permit independent expansion and contraction of said cores but prevent the headers of said pair of headers from moving vertically or longitudinally relative to each other.
